UNITED STATES PATENT OFFICE.

JOSIAH F. DAY, OF NEW YORK, N. Y.

DUMPING-WAGON.

SPECIFICATION forming part of Letters Patent No. 714,286, dated November 25, 1902.

Application filed September 16, 1902. Serial No. 123,622. (No model.)

To all whom it may concern:

Be it known that I, JOSIAH F. DAY, a citizen of the United States, residing at New York, in the county of New York and State of New York, have invented certain new and useful Improvements in Dumping-Wagons; and I do hereby declare the following to be a full, clear, and exact description of the invention, such as will enable others skilled in the art to 10 which it appertains to make and use the same.

The present invention relates to improvements in vehicle-bodies, and particularly to the dumping type, the object in view being the production of a body having doors forming 15 the bottom thereof and loosely mounted, so as to be capable of vibration when in an open condition.

In constructing a vehicle-body after the manner of the present invention a further object is attained in the particular means of supporting the doors forming the body, whereby said doors may be caused to assume an inclined plane when in an open condition, with the upper edges thereof lying beneath the 25 lower edges of the side-boards of the vehicle.

With these and other objects in view the invention consists of certain novel constructions, combinations, and arrangements of parts, as will be hereinafter fully described 30 and claimed.

In the accompanying drawings, Figure 1 represents a view in side elevation of a vehicle-body embodying the features of the present invention. Fig. 2 represents a transverse vertical section taken on the plane of line 2 2 of Fig. 1. Fig. 3 represents a top plan view of the structure disclosed in Fig. 1. Fig. 4 represents an enlarged detail fragmentary perspective view of a portion of one of 40 the doors, illustrating the chain hinges therefor. Fig. 5 represents an enlarged, detail fragmentary view of one of the supporting chain brackets.

In the art to which the present invention 45 relates vehicle-bodies have been constructed with doors forming the bottoms thereof and hinged to the side-boards rigidly, so as to swing downwardly and assume a vertical plane when in an open condition, and it is 50 further common in the art to support the doors forming the bottom of the body of a vehicle by chains attached on the inside of the side-boards, whereby the said doors assume vertical planes and extend within the

vehicle-body when in an open condition; but 55 serious objections have arisen to both the constructions described, in that in closing the doors after a discharge of the contents of the vehicle-body quantities of the load carried by the vehicle are usually caught by the 60 edges of the doors and cause the same to spring and become jammed, loosening the connecting and supporting parts and sometimes causing a serious injury to the doors, the prime object of the present invention being 65 to avoid these serious results by providing means whereby there is the least possibility of either of the doors collecting any of the matter being discharged from the body of a vehicle and, further, whereby the small 70 quantity which may accidentally come in contact with said edges will be forced therefrom by the closing movement of the door without any springing or binding action upon the parts. These valuable functions are 75 attained by the present invention, one embodiment of which is depicted in the accompanying drawings, in which 1 indicates any suitable vehicle-body made up of side-boards 2 2 and front and rear end-gates 3 3, which latter may be of any suitable construction and positioned on diagonal planes or vertical, as 80 may be desired. The bottom of the body 1 is formed of doors 4 4, each of which has attached thereto a plurality of chain hinges 5, 85 each of said hinges being made up of a chain attached to the outside of a side-board, as at 6, and to a door, as at 7, a suitable wearing-plate, as 8, being secured to each of the respective doors 4 at the point of the hinge for receiving the wear therefrom, the said plate being preferably cupped, as indicated in Fig. 4. A plurality of braces 9, of suitable material, 90 preferably metal, extend downwardly from each of the side-boards 2 2 past the upper edge 95 of each of the respective doors 4 for bracing the same when in a closed position and limiting the same against lateral movement when open. Attached to the inside of each door 4, 100 preferably near the inner edge thereof, is a chain 10, which extends upwardly through the respective side-board 2 about a pulley 11, carried by a bracket 12, extending laterally from said side-board, and the chain thence extends forwardly and is attached to a winding-shaft 13, which shaft may be provided with 105 any preferred form of pawl-and-ratchet locking mechanism 14. Each chain 10 is of a

length sufficient to permit the door 4 to which it is attached to swing to a diagonal plane, preventing the same from assuming a vertical position.

- 5 In operation the load is contained within the body 1 upon the doors 4, the said doors being sustained in a closed condition by means of the chains 10 and locked against release by the pawl-and-ratchet mechanism 14. When 10 it is desired to discharge the contents of the vehicle-body, the mechanism 14 is released and the doors 4 dropped under the weight of the contained load, said doors in dropping assuming diagonal planes owing to the supporting 15 chain hinges 5 and the chains 10, whereby the upper edges of said doors are held beneath the respective edges of the side-boards, thereby obviating to a great extent the danger of foreign matter being lodged upon the 20 said upper edges of the doors. After the load has been discharged it is only necessary to wind the shaft 13 to lift the doors to a closed position, said doors in the lifting movement bringing their inner corners first into contact 25 with the inner corner of the respective side-board and the said corner of the door then moving transversely across the lower edge of the side-board and driving before it any foreign matter which may possibly have been retained 30 by the said edge or which may have become lodged upon the lower edge of the side-board, whereby each door 4 is self-cleaning, the cleaning operation being performed each time the door is closed.
- 35 In the repairing of roads it is often found desirable to discharge a small quantity of crushed stone at a given point, and this is usually accomplished by shoveling the desired quantity from the supply-vehicle, and 40 in order to obviate the necessity for this shoveling process I contemplate providing each door with a sliding gate 15, provided with a suitable operating-handle 16 and slidably retained in position by any preferred form of 45 frame 17, attached to the respective door. When only a small quantity of contained material is desired to be deposited, it is only necessary to grasp the handle 16 and withdraw the gate 15 to the desired extent, then 50 replace the same, the contained material automatically discharging itself and the discharge being cut off by the closing of the door.
- 55 Although I mention "chains" throughout the specification, it will be understood that where such term is used I refer to any suitable cable and do not limit myself to a link construction, and it will further be understood that I am aware that it is old in the art to employ brackets for guiding the chains 10 60 in the manner disclosed, so that I shall not limit myself to any particular construction of brackets and do not desire to be understood as posing as the inventor of a chain passed through the side-board, but may 65 change this construction as I may find desirable at will, the disclosure of the particular device mentioned being the best for illustra-

tive purposes of the present invention. Other features of the structure may be altered as may be found necessary, and I shall not consider myself limited to the minor details herein specified, but shall deviate therefrom to any extent within the spirit and scope of the present invention.

Having now described my invention, what I claim as new, and desire to secure by Letters Patent, is—

1. In a vehicle-body the combination with side-boards, of doors forming the bottom of said body, and chains connecting the under 80 sides of said doors with the outside of said side-boards, and supporting said doors when in an open condition with the upper edges thereof normally beneath the lower edges of the respective side-boards, the upper edges of 85 said doors being left free to swing or vibrate, substantially as described.

2. In a vehicle-body, the combination with suitable side-boards, of doors forming the bottom of said body, flexible hinges connecting the outside of said doors with the outside of said side-boards and having the upper edges thereof free for lateral movement when the doors are in an open condition, and means for supporting said doors in a closed condition, substantially as described.

3. In a vehicle-body, the combination with suitable side-boards, of doors forming the bottom of said body, chain hinges connecting the outside of said doors directly to the outside of said side-boards, and means for supporting said doors in a closed condition, substantially as described.

4. In a vehicle-body, the combination with suitable side-boards, of doors forming the bottom of said body, flexible hinges connecting said doors directly to the outside of said side-boards, and independent means for limiting said doors from swinging beyond a diagonal plane when being opened, substantially as described.

5. In a vehicle-body, the combination with suitable side-boards, doors forming the bottom of said body, flexible means between each of said doors and the outside of its respective side-board, a cable connected with each of said doors, and means for swinging said cable for closing the doors, substantially as described.

6. In a vehicle-body, the combination with suitable side-boards, of doors forming the bottom of said body, flexible means connecting said doors and the outside of said side-boards, said doors being left free to swing thereon, braces secured to the side-boards and 125 extending beyond the edges of said doors, and means for supporting said doors in a closed position, substantially as described.

In testimony whereof I hereunto affix my signature in presence of two witnesses.

JOSIAH F. DAY.
